UNITED STATES PATENT OFFICE.

EDINBURGH GRAHAM, OF AIKEN, SOUTH CAROLINA.

MONOSLOT TOILET ROOM.

Application filed April 12, 1924. Serial No. 706,213.

This invention relates to a room or cabinet particularly useful as a toilet room.

A prime aim is to provide a construction in which use by a single patron at a time without accidental intrusion or interference by others, is assured.

A second object is to devise a form which may be built around an already-set toilet stool if desired, to convert it into a pay toilet.

Another object is to produce a structure operable through a coin-controlled means which is concealed and inaccessible for operation from the outside while the room is in use.

A further aim is to construct a toilet room possessing the advantages stated, in which its closure has spaced walls between which the patron enters, the innermost of which walls is cut away so as to expose the toilet stool or parts for the use of which a fee is charged.

A fifth object is to invent a novel coin-controlled means to particularly cooperate with a room of the character set forth.

Various additional objects and advantages will appear from a consideration of the description following, taken in connection with accompanying drawings illustrating an operative embodiment.

In said drawings:

Fig. 1 is a view in side elevation, partly broken away, showing the coin-controlled latch means for the closure employed;

Fig. 2 is a view in section, taken on the line Y—X of Fig. 1;

Fig. 3 is a longitudinal sectional view taken on the line A—B of Fig. 1;

Fig. 4 is a perspective view of the latch-operating lever;

Fig. 5 is a perspective view of the latch-bolt;

Fig. 6 is a perspective view of one of the outer plates of the latch casing;

Fig. 7 is a perspective view showing intermediate parts of the latch and casing;

Fig. 8 is a perspective view of the other outer plate of the latch casing;

Fig. 9 is a vertical sectional view through the complete apparatus taken on a line intermediate the front and rear walls of the closure;

Fig. 10 is a horizontal sectional view through the complete apparatus;

Fig. 11 is a vertical sectional view through the complete apparatus and at a right angle to Fig. 9;

Fig. 12 is a perspective view of the complete apparatus;

Fig. 13 is a detail illustrating part of the mounting for the latch operating lever;

Fig. 14 is a perspective view of the coin till, and

Fig. 15 is a perspective view illustrating the mortise and tenon connection as used between the structural elements of the cabinet.

Referring to the operative embodiment disclosed by way of example in the accompanying drawings, a toilet stool is illustrated at 9 supported on a floor 10 and adjacent the stool a wash basin or lavatory 11 may be provided. Said stool and wash basin are located within a room 12. The showing of the room is to be taken as conventional since the room may be one as ordinarily constructed in a building or it may be a cabinet as shown in the drawings. Since it may be a cabinet, the structure such as 12 may even be portable and adapted to be placed about an already set toilet stool 10 and wash basin 11, should it be desirable or advantageous to convert a free toilet into a pay toilet.

Said cabinet 12 is generally rectangular having a rear wall 13, a side wall 14, a shorter side wall 15, an upright 16, all anchored to floor 10, and a cover 17. Said walls are built up in any preferred way as from uprights and panels as shown. The wall 15 may be of slatted construction as at 15^a to afford ventilation. As the wall 15 is spaced from the upright 16, an entrance and exit opening is provided at 18. The necessary operating equipment for the toilet stool 10 and wash basin 11 is located within the room 12, and if desired, may be supported on the walls 13, 14 and 15 thereof as shown.

Coating with the room or cabinet 12 is a closure generally designated 19. This closure consists of spaced upstanding walls 20 and 21 arranged parallel to each other and to the end wall 13. Wall 21 may be slatted as shown for ventilation. Connecting bars or members 22 adjacent to the wall 14 rigidly join the walls 20 and 21 together so that they may be moved as a unit. An entrance and exit opening 23 is provided for the closure and restricted by means of a wall 24

fastened to wall 21, which aids in better closing of opening 18 when the apparatus is being used.

Fastened to the uppermost connecting bar 22 at each side of the closure, is a pair of brackets 25. Each bracket 25 has a roller 26 journaled on a bolt 27 secured thereto and the rollers are adapted to travel on the inner edge portions of U-shaped tracks 28 fastened 10 as at 29 to the walls 12 and 14, adjacent to the tops of the latter. As a result, the closure 19 may be moved longitudinally or back and forth within the room or cabinet from the full line position shown in Figs. 10 and 11 to the dotted line position suggested in the same figures. The patron is adapted to walk through the openings or ways 18 and 23 to a position between the walls 20 and 21 and into the room while the closure moves toward the end wall 13. The patron will thus have access to the stool 9 and wash basin 11 since the wall 20 is recessed or cutaway as at *a* and *b*, to enable the same to occupy a position at the rear of stool 9:

The apparatus is used as a pay toilet and a suitable coin controlled lock or latch means is accordingly employed. To this end, a longitudinal securing bar 30 is fastened as at 31 against the inner surface of the wall 14. The bar 30 is provided with ratchet teeth as at 32 whose inclined faces slant downwardly from vertical shoulders toward the wall 13.

Coacting with the securing bar 30 is a lock or latch casing 33 carried by the closure 19. Said casing is freely movable relatively to the bar 30 since the latter is accommodated in slots 34 in the end walls of a cover plate 35 of such casing. Bolts 36 secure said cover plate 35 rigidly to that connecting member 22, which is in line with securing bar 30. Casing 33 also has an outer plate 37, an inner plate 38 and an intermediate plate 39 which are also secured rigidly in place by the said bolts 36. The inner plate 38 has a bracket portion 40 provided with a stud 41 on which a roller 42 is journaled and on which roller the bar 30 rests and is guided. A supplemental intermediate plate or filler 43 is also fastened in place by certain of the bolts 36. Below the supplemental plate 43 a coin-controlling finger 44 is provided for pivotal movement on the axis of a pin 45. Said plates 39 and 43 and finger 44 are spaced apart as best shown in Figs. 1 and 7, to provide a coin-receiving slot S. A pawl-lifting member 46 is vertically slidable in a slot 47 of the plate 39 and is normally in its lowermost position so as to serve as an abutment for a coin like that at C, when deposited in slot 46.

In spaced inwardly extending lugs 48 of plate 38 a pawl 49 is slidably mounted. Said pawl 49 coacts with the securing bar 30 to prevent unauthorized operation of the closure 65 and it is urged into engagement with said

bar by a spring in the form of a wire 50 which engages in a notch 51 at the top of the pawl 49. Said spring 50 is fastened in inwardly extending ears 52 of the plate 38. The pawl 49 has a slot at 53 in which the forwardly extending lug 54 at the top of the lifting member 46 is disposed, whereby the pawl 49 and trigger 46 will slide or move up and down unitarily. Depression of the pawl 49 is limited by the engagement of a shoulder 55 on said pawl against the lowermost lug 48.

A generally U-shaped operating lever 56 is employed for the coin-controlled mechanism. Said lever 56 has a relatively long horizontal bar 57 and upstanding terminal arms 58 and 59. The pin or element 45 is rigidly connected to both the bar 57 and the lifting finger 44 so that they will move as a unit and will fulcrum from the axis of element 45 since the latter is journaled in the plate 37, it being realized that the bar 57 and lifting finger 44 are located on opposite sides of said plate 37. The lifting finger 44 and bar 57 are further rigidly connected together by fastenings in the form of rivets 58'. Said fastenings 58' pass through slots or holes 59 in the plate 37 and in said holes the fastenings 58' have disks or washers 60 surrounding the same and properly spacing the parts. Said holes 59 are larger than the washers 60 in order to permit limited unitary pivotal movement of lever 56 and the lifting finger 44. It is to be understood that the lifting finger 44, fastenings 58', and washers 60 are so proportioned as to give ample clearance for effective movement of the lifting finger 44.

Arm 58 of lever 57 has a finger piece 61 at its top for engagement by the patron's fingers to depress the same. Movement of the lever 56 both upwardly and downwardly is limited by a check 62 which is fastened to the outer plate 37. Said check has curled extremities 63 for direct abutment by the bar 57 of the lever in the uppermost and lowermost limits of movement of the lever and such bar 57 is outwardly offset as shown adjacent said check. A cord or other flexible element 64 is tied to the arm 59 and is trained over a pulley 65 journaled on a stub shaft 66 carried by a bracket 67 fastened against the inner surface of the stationary end wall 13 of the room. At the lower or free end, said cord 64 carries a weight 68 which is designed to automatically urge and move the closure from the full line of the dotted line position in Figs. 10 and 11 upon the pawl 49 disengaging the bar 30, following deposit of a coin and appropriate actuation of lever 56.

The coins from slot S are received in a suitable till 69 which is pivoted at 70 to the casing 33. The casing and till have openings 71 adapted to register and to receive 130

the shackle of a padlock 72 or the equivalent therethrough in order to fasten the till against tampering. At desired times the proprietor may remove padlock 72 and swing the till 69 downwardly as in Fig. 1, to remove the coins.

Toilet paper may be carried by a holder rod 73 as in rolls 74 threaded thereon. Rod 73 removably passes through the wall 21 and a bracket 75 on the same connecting bar 22 to which the lock casing 33 is fastened and said rod 73 is secured against unauthorized removal by a head at the outer end thereof and a padlock or the like 76 which is passed through an eyelet 77 at the inner end thereof.

In order to limit the movement of the closure toward the wall 13, a strap 78, generally of U-shape, may be carried at the base 20 of wall 20 and arranged to abut the stool 9 adjacent its base in the innermost or dotted line position of the closure.

Bar 30 has a cam 79 thereon to coact with the pawl 49 to release coins from slot S.

Presuming operation, the parts are initially in the full line position of Fig. 10 and so held by the engagement of pawl 49 with securing bar 30. The user walks through the openings 18 and 23 and occupies a position within the closure, that is between the walls 20 and 21. Thereupon the proper coin C is deposited in the slot S, traveling until it is arrested by the lifting finger 46. Thereupon the patron depresses lever 56 by engagement with the finger piece 61 to the extent limited by the lowermost curl 63 of check 62. Such depression of lever 56 moves the coin end of coin controlling finger 44 downwardly so that the coin travels under the lifting finger 46, still being held from complete escape from slot S by said finger. The finger piece 61 is then released and the action of the weight 68 serves to elevate the end of lever 56 adjacent to arm 58, accordingly elevating the coin end of finger 44, the coin C, finger 46, and pawl 49, causing the latter, against the tension of its spring 50, to disengage the ratchet teeth of securing bar 30. The weight 68 thereupon automatically urges and moves the closure from the full line position in Figs. 10 and 11 to the dotted line position, with the patron following the movement of the closure and thus walking into the room which it will be realized, is closed at the entrance end by the wall 21.

When the closure approaches its innermost position, pawl 49 strikes the cam surface 79 on the bar 30, which further elevates said pawl 49, thus releasing the coin C so that it may fall into the till 69. Thus the patron is within the room and finds the stool 10, wash basin 11, and paper 74 accessible for use. In leaving the room or cabinet, the patron pushes the wall 20 forwardly

from the dotted line position to the full line position, with the weight 68, thus being elevated and with the pawl 49 idling over the ratchet teeth 32 and automatically positioning itself for a subsequent operation.

Proper outward movement of the closure by the patron permits him to leave through the openings 23 and 18.

When the patron is within the room his presence between the walls 20 and 21 prevents any tampering with a view to moving the closure outwardly for unauthorized use of the apparatus by other persons. Also while the patron uses the apparatus, the coin-controlled means is concealed so that other coins cannot be deposited therein to interfere with operation by prospective patrons.

Various changes may be resorted to provided they fall within the spirit and scope of the invention.

Having described my invention, what I claim as new and desire patent for is:—

1. A room structure having a closure, said closure being provided with spaced defining walls for entrance of the user therebetween, said walls being unitarily movable to and from open position while the user is located therebetween, said walls in the closed position of the closure serving as defining walls for the room space.

2. A room structure having a normally open closure, movable to and from open and closed position, said closure being of a construction for initial entry by the user, and operated by the user while located therein, a room structure coacting with the closure in the closed position of the latter to close the room on all sides.

3. A room structure having spaced walls, a closure therefor having spaced defining walls for initial entry of the user therebetween, said walls being unitarily movable to and from open position while the user is located therebetween, the walls of the room structure and closure in the closed position of the latter serving to close the room on all sides.

4. A room structure having a closure movable to and from open and closed position, said closure having spaced walls and an entrance opening, the innermost wall being cut away to enable the same to move past the contents of the room and the structure to close said opening.

5. A room structure having a closure movable to and from open and closed position, a plumbing fixture in the room space, said closure having spaced walls and an entrance opening, the innermost wall being cut away to enable the same to move past the plumbing fixture and the structure to close said opening.

6. A room structure having a closure movable to and from open and closed position, a

plumbing fixture in the room space, said closure having spaced walls and an entrance opening, the innermost wall being cut away to enable the same to move past the plumbing fixture and the structure to close said opening, and an element on the closure to abut the plumbing fixture.

7. In combination, a room structure, a closure structure therefor, one of said structures having an entrance opening, one of said structures being telescopically movable relatively to the other structure for entrance of a user and closing of said opening by the companion structure.

8. In combination, a room structure, a closure structure therefor, one of said structures having an entrance opening for the user and being telescopically movable relatively to the other structure after entrance of the user to close said opening and give access to the room space.

9. In combination, a room structure, a closure structure therefor, one of said structures being telescopically movable relatively to the other structure and having an opening for entrance of a user, and means under control of the user operable to move the closure to closed position to close said opening.

10. In combination, a room structure, a closure structure therefor, one of said structures being telescopically movable relatively to the other structure and having an opening for entrance of a user, and means locking the closure in open position under control of the user to permit movement of the closure to closed position to close said opening.

11. In combination, a room structure, a closure structure therefor, one of said structures being telescopically movable relatively

to the other structure for entrance of a user, and coin-controlled means locking the closure in open position under control of the user to permit movement of the closure to closed position.

12. In combination, a room structure, a closure structure therefor, one of said structures being telescopically movable relatively to the other structure for entrance by a user, coin-controlled means locking the closure in open position under control of the user to permit movement of the closure to closed position, and means operable to move the closure to closed position.

13. A room structure having a closure, means automatically operable through opening movement of the closure to maintain the closure in open position, said means being coin-controlled for release so that the closure may be closed.

14. A room structure having a closure, coin-controlled means to maintain the closure in open position, and means operable automatically to move the closure to closed position, after operation of the coin-controlled means.

15. A room structure having a closure, a lock means to hold the closure in one position, and means to urge movement of the closure to the other position, the latter means being connected to said lock means.

16. A room structure having a closure, a lock means to hold the closure in one position, an actuating lever for said lock means, and means to urge movement of the closure and said lever to locking position, the latter means being connected to said lever.

EDINBURGH GRAHAM.
